CLAIM

We claim the ornamental design for an extruded frame member, as shown and described.

DESCRIPTION

FIG. 1 is a perspective view of an extruded frame member embodying the invention.

FIG. 2 is a first side view of the extruded frame member of FIG. 1.

FIG. 3 is a second side view of the extruded frame member of FIG. 1.

FIG. 4 is a front view of the extruded frame member of FIG. 1.

FIG. 5 is a rear view of the extruded frame member of FIG. 1.

FIG. 6 is a top view of the extruded frame member of FIG. 1; and,

FIG. 7 is a bottom view of the extruded frame member of FIG. 1.

The broken lines in the drawings illustrate portions of the extruded frame member that form no part of the claimed design.

The extruded frame element is shown with a symbolic break in its length. The appearance of any portion of the extruded frame element between the break lines forms no part of the claimed design.

1 Claim, 6 Drawing Sheets
